Filed June 5, 1961, Ser. No. 65,452

Term of patent 14 years

(Cl. D26—5)

FIG. 2

FIG. 2

FIG. 3

FIG. 4

FIG. 1 is a perspective view of a computer console, showing my new design;

FIG. 2 is a front elevational view;

FIG. 3 is a side elevational view, the opposite side being substantially a mirror image thereof; and

FIG. 4 is a cross-sectional view of one of the support members taken along line 4-4 in FIG. 3.

A portion of the upright support is broken away for convenience in illustration to disclose the preferred extent of the supporting structure which in the illustrated embodiment extends from the floor to the ceiling. Portions of FIGS. 1 and 2 are diagonally lined to indicate transparency.

I claim:

The ornamental design for a computer console, substantially as shown and described.
